MOLDING CLIP

William E. Wiley, Detroit, Mich.

Application October 28, 1938, Serial No. 237,391

4 Claims. (Cl. 189—88)

The present invention relates to clips for mounting sheet metal molding strips to sheet metal panels, and particularly relates to an improved clip structure over that disclosed and claimed in the United States Letters Patent to William R. Wiley, No. 2,084,717, patented June 22, 1937.

One of the primary objects of the present invention is to provide an improved clip structure which cannot be accidentally or intentionally removed from the panel to which it is attached by the application of pressure exteriorly of the panel and which can only be removed by first collapsing it from the under side of the panel. Another object of the invention is to provide an improved clip structure which may be forced into position through an opening in the panel by the application of less pressure than that needed to set prior types of clips. Other objects of the invention will become apparent from the following specification, the drawing relating thereto, and from the claims hereinafter set forth.

In the drawing, in which like numerals are used to designate like parts in the several views throughout:

Figure 1 is a fragmentary cross-sectional view, with parts in elevation, of a sheet metal molding strip attached to a panel by an improved clip according to the present invention;

Fig. 2 is a perspective view of the clip illustrated in Fig. 1;

Fig. 3 is a cross-sectional view taken substantially along the line 3—3 of Fig. 1;

Fig. 4 is a view similar to Fig. 1 illustrating a modified form of the present invention; and

Fig. 5 is a cross-sectional view taken substantially along the line 5—5 of Fig. 4.

Referring to the drawing, and referring particularly to Figs. 1 through 3 thereof, a sheet metal channel-shaped molding strip 10 is illustrated having the usual inturned edges 12. It is, of course, to be understood that the strip 10 is elongated in shape and is adapted to be attached to a sheet metal panel 14, such as one of the body panels of an automobile, at spaced intervals along its length. The panel 14 is provided with a plurality of spaced openings or apertures 16 along the line which the molding strip is designed to occupy when in position.

The molding 10 is adapted to be secured to the panel 14 by means of clips, generally indicated at 18, which engage the molding strip 10 and engage the panel 14 through the openings 16. The clip 18 comprises a hardened and tem-

pered sheet metal strip having the central portion thereof arched, as indicated at 20, to provide an arched head for reception within the molding 10. The next adjacent portions 22 are bent so that they converge inwardly to form a neck 5 of appreciably less breadth than the head or arched portion 20. The base of this neck is indicated at 24, and those portions of the clip indicated at 26 adjacent the base 24 are then bent so that they diverge outwardly to provide 10 shoulders which are adapted to bear against the under edge of the opening 16 when the clips are in position. The converging portions 22, base 24, and diverging portions 26 form indentations in the clip in which the converging portions 22 bear 15 against the facing edges of the flanges 12 and the outwardly diverging portions 26 bear against the under edges of the openings 16 to fix the molding 10 relative to the panel 14. The clips 18 may be applied to the molding 10 in the manner described in the Wiley patent referred to.

The end portions 28 of the clip, adjacent the outwardly diverging portions 27, converge toward each other to provide a resilient prong adapted for insertion into the aperture 16 in 25 the panel 14. The end portions 28 meet at the lowermost point of the clip, and one of such end portions is longer than the other and is bent over the plain end of the other, as indicated at 30, as in the structure described in the patent referred to.

In the patent referred to, the legs forming the prongs are generally straight, and according to the present invention in order that the clips may be applied to the panel with less pressure, 35 the end portions 28 are arched outwardly over a portion of their length adjacent the portion 26 about the radii indicated at R. It has been found that by providing these outwardly arched parts in the prong portion of the clip, the force required to insert the clips into the panel is reduced about twenty per cent. It has also been found that this arching of the prong legs prevents the clip from breaking down and permanently collapsing as the arched sections seem to 45 throw most of the pressure into the neck 24.

The present invention is primarily concerned with means formed on the clip to prevent the accidental or intentional removal of the clip from the panel 14 by the application of pressure 50 through a tool or otherwise to the head 20 or the clip adjacent the neck 24 from the outside of the panel 14. This means includes the provision of oppositely and outwardly disposed recesses 32 in the edges of the diverging portions 26. These re-

cesses provide edges or shoulders 34. The recesses 32 are so shaped that the edges 34 are positioned in slightly spaced relation to the under surface of the panel 14. As best shown in Fig. 3, these recesses provide a shoulder formed by the edge 34 which underlies the edge of the apertures 16. The recesses 32 and shoulders 34 do not in themselves serve as part of the normal means for holding the clip in position and for mounting the molding to the panel as the clip construction itself serves this purpose. The recesses and shoulders merely serve to lock the clip in position and to prevent its removal from its opening 16 upon the application of pressure through a tool or otherwise to the molding or clip from the outside of the panel 14. When such pressure is applied, the shoulder or edge 34 would abut against the under edge of the opening 16 so that the clip would be stopped in any outward movement. The clip can only be removed by collapsing it from the under side of the panel 14.

In Figs. 4 and 5, a modified form of the invention is illustrated in which instead of providing the recesses 32, tabs 40 are struck outwardly from the diverging portions 26 of the clip. As shown in Fig. 4, the tabs 40 are of such a length that they are normally, slightly spaced from the under edge of the panel 14. The clip 18 may be readily inserted through the opening 16, but any attempt to remove the clip from the outside of the panel would result in the tabs 40 striking against the panel 14 adjacent the opening 16. The clip cannot be removed without collapsing it from the under side of the panel.

35 Formal changes may be made in the specific embodiment of the invention described without departing from the spirit and substance of the invention, the scope of which is commensurate with the appended claims.

36 What is claimed is:

40 1. In combination, a generally channel-shaped molding strip having inturned flanges at its lateral edges, a sheet metal panel having an aperture therein, and a clip for securing said molding strip to said panel, said clip comprising a sheet metal strip formed into a closed loop, said clip being shaped to provide indentations in opposite sides thereof, the portion of said strip between said indentations being generally arched to resiliently urge the bases of said indentations into engagement with the inturned flanges on said molding strip, the remaining portions of said strip diverging from the bases of said indentations to provide cam surfaces for urging said molding strip into engagement with said sheet metal panel and then converging to provide a prong for facilitating the insertion of said clip into the aperture in said panel, and means formed on the diverging portions of said clip so constructed as to normally be spaced from the adjacent side of said panel and movable into engagement with said panel in the event that outward pressure is applied to said arched portion.

65 2. In combination, a generally channel-shaped molding strip having inturned flanges at its lateral edges, a sheet metal panel having an aperture therein, and a clip for securing said molding strip to said panel, said clip comprising a sheet metal strip formed into a closed loop, said

clip being shaped to provide indentations in opposite sides thereof, the portion of said strip between said indentations being generally arched to resiliently urge the bases of said indentations into engagement with the inturned flanges of said molding strip, the remaining portions of said strip diverging from the bases of said indentations to provide cam surfaces for urging said molding strip into engagement with said sheet metal panel and then converging to provide a prong for facilitating the insertion of said clip into the aperture in said panel, and means forming outwardly disposed recesses in the edges of the diverging portions of said clip having shoulder portions located adjacent said aperture so constructed as to normally be spaced from the adjacent side of said panel and movable into engagement with said panel in the event that outward pressure is applied to the arched portion.

3. In combination, a generally channel-shaped molding strip having inturned flanges at its lateral edges, a sheet metal panel having an aperture therein, and a clip for securing said molding strip to said panel, said clip comprising a sheet metal strip formed into a closed loop, said clip being shaped to provide indentations in opposite sides thereof, the portion of said strip between said indentations being generally arched to resiliently urge the bases of said indentations into engagement with the inturned flanges on said molding strip, the remaining portions of said strip diverging from the bases of said indentations to provide cam surfaces for urging said molding strip into engagement with said sheet metal panel and then converging to provide a prong for facilitating the insertion of said clip into the aperture in said panel, and means forming oppositely and outwardly disposed recesses in the edges of the diverging portions of the clip having shoulder portions located adjacent said aperture so constructed as to normally be spaced from the adjacent side of said panel and movable into engagement with said panel in the event that outward pressure is applied to the arched portion.

4. In combination, a generally channel-shaped molding strip having inturned flanges at its lateral edges, a sheet metal panel having an aperture therein, and a clip for securing said molding strip to said panel, said clip comprising a sheet metal strip formed into a closed loop, said clip being shaped to provide indentations in opposite sides thereof, the portion of said strip between said indentations being generally arched to resiliently urge the bases of said indentations into engagement with the inturned flanges on said molding strip, the remaining portions of said strip diverging from the bases of said indentations to provide cam surfaces for urging said molding strip into engagement with said sheet metal panel and then converging to provide a prong for facilitating the insertion of said clip into the aperture in said panel, and means forming outwardly disposed abutments on the diverging portions of the clip so constructed as to normally be spaced from the adjacent side of said panel and movable to abut against said panel in the event that outward pressure is applied to the arched portion.
